(57) **CLAIM**

The ornamental design for a television receiver with stand, as shown and described.

DESCRIPTION

1. Television receiver with stand

1.1 : Front perspective view

1.2 : Back perspective view

1.3 : Front

1.4 : Back

1.5 : Left

1.6 : Top

1.7 : Bottom

1.8 : Enlarged

1.9 : Front perspective view

1.10 : Back perspective view

1.11 : Front

1.12 : Back

1.13 : Left

1.14 : Top

1.15 : Bottom

The claimed design is a television receiver with stand in which a base plate is provided on the rear side of a display for adjusting the height; reproductions 1.1 to 1.8 show a state of the claimed design before change; reproduction 1.8 is an enlarged view of the encircled portion in reproduction 1.2; reproductions 1.9 to 1.15 show an alternate state of the base plate supporting a display moved up; a right view in each of the states is omitted because it is a mirror image of the left view; the evenly-spaced broken lines shown in the reproductions depict portions of the television receiver with stand that form no part of the claimed design; the dot-dot-dash broken lines in reproductions 1.2 and 1.8 indicate the boundary of the enlarged view and form no part of the claimed design; the shading lines are used to show the surface of the claimed design and do not represent its surface ornamentation.

1 Claim, 15 Drawing Sheets
